UNITED STATES PATENT OFFICE.

ORLANDO D. PRESCOTT, OF NEW YORK, N. Y.

ELECTRIC RAILWAY.

No. 876,659.

Specification of Letters Patent.

Patented Jan. 14, 1908.

Application filed May 25, 1906. Serial No. 318,715.

To all whom it may concern:

Be it known that I, ORLANDO D. PRESCOTT, a citizen of the United States, residing at New York, N. Y., have invented certain new and useful Improvements in Electric Railways, of which the following is a specification.

This invention relates to electric railways, having special reference to that class in which the "third rail" or working conductor is arranged adjacent the way or tracks and parallel thereto and maintained in an inverted position so that the trolley or current collecting shoe carried by the car engages the under surface of the contact rail.

The primary object of the invention is to provide improved, simple and efficient means for supplying current to the car motor from the contact rail.

So far as I am aware, the broad idea to which my invention relates has failed of universal adoption because of the extensive workmanship required by the means heretofore suggested, such as the provision of pedestals or brackets to support the third rail and in the provision of insulation between the rail and its support, and because the wires or other current conductors leading to the motor have been so connected to the shoe supporting means that in the event of accident causing the support to break the wires also have been broken and hence a great deal of time and labor have been involved in effecting repairs.

The invention will be hereinafter fully set forth and particularly pointed out in the claims:

In the accompanying drawing Figure 1 is a plan view showing a car truck equipped with a trolley constructed in accordance with my invention and in engagement with the working conductor. Fig. 2 is a view partly in cross section and partly in side elevation of the same parts. Fig. 3 is a perspective of the inner side of the working conductor. Fig. 4 is a detail view of the support for the contact shoe.

Referring to the drawings, 1 designates the way or tracks of any preferred construction. The working conductor is shown comprising a series of sections, each section being made of a single piece, preferably a plate of cast iron and bent to form the upright portion 2 T-shaped at its lower portion 3 and suitably mounted as by chairs 4 on the ties or sleepers 5. The upright portions 2 of each section taper upwardly to insure their being evenly

balanced and are bent as at 6 toward the way or tracks 1 and thence downwardly, terminating in a rail 7. This rail 7 is the working conductor, proper. The meeting edges of adjacent working conductor sections are secured together by plates spanning the edges and held by bolts 8, as shown in Fig. 3. It will be understood that current is supplied to this third rail to be collected therefrom by the trolley or shoe.

The means shown for supporting the contact shoe comprises a plate 9 of cast iron or other conducting material secured to and carried by the car truck or frame, as by the equalizing bar indicated at 10. I have shown a wire conductor 12 attached directly to plate 9 and designed to conduct the current from the latter to the car motor. Depending from either end of the plate 9 is an arm 13. These arms are connected at their lower ends by a shaft or journal 14 upon which are pivoted ears 15 of the trolley supporting arms 16 carrying at their outer ends the current collecting shoe 17. Springs 18 are secured to the arms 16 and to plate 9 and tend to hold the arms 16 and the shoe above a horizontal position so as to insure effective contact between the shoe and the working conductor.

In order to prevent the shoe being forced too far above the plane of the working conductor I have shown each of the arms 16 provided with an ear or lug 19 designed to be engaged by stops 20 and 21 on the front and rear edges of the arms 13.

It is desirable in the manufacture that the ears 15 and lugs 19 of each of the trolley supporting arms be formed of a single piece of metal so that they may present a smooth surface to the inner faces of the arms 13. It will be understood that these arms 13, as well as the shaft 14, the arms 16 and the ears 15 and lugs 19 are made entirely of conducting material, preferably cast iron. By this means the current collected by the shoe from the working conductor is transmitted through the entire trolley support to the wire conductor 12 regardless of the angle at which the arms 16 may be disposed, since the current will be conducted from these arms through the ears 15 and lugs 19 which bear against the inner faces of the arms 14.

From what has been said the advantages of my invention will be apparent to those skilled in the art. In addition to the obvious simplicity of construction and conse-

quent cheapness of installation, it will be noted that the invention requires few parts not likely to become broken or deranged. If, however, the shoe or its supporting arms should be broken by accident another may readily be substituted since it is only necessary to remove the shaft 14 in order to separate the arms 16 from their supports. At the same time, as will be appreciated by 10 trainmen, the conductor wire leading to the motor is not interfered with, or, at least, is not likely to be in any of the commonly occurring accidents causing damage to the shoe.

15 I claim as my invention:—

In an electric railway, the combination with the way or tracks and the working conductor arranged adjacent the way and parallel thereto, of a frame designed to be 20 rigidly mounted on a car movable on said way, a conductor wire leading from said frame to the car motor, said frame having

side arms, a shaft connecting said arms, a trolley support having plates or flanges journaled on said shaft and forming engaging lugs or projections, stops on the inner faces of said arms designed to co-act with said lugs to limit the movement of said support, said plates or flanges contacting with the faces of said arms, and a trolley or current collecting shoe carried by said support and engaging said working conductor, all of said parts comprising the trolley support being of conducting material, for the purpose stated.

In testimony whereof, I have signed my name to this specification in the presence of two subscribing witnesses, this 12th day of May 1906.

ORLANDO D. PRESCOTT.
